UNITED STATES PATENT OFFICE.

WILLIAM C. HOMAN, OF MERIDEN, CONNECTICUT, ASSIGNOR TO THE
EDWARD MILLER & COMPANY, OF SAME PLACE.

DESIGN FOR A SHADE-HOLDER.

SPECIFICATION forming part of Design No. 30,100, dated January 31, 1899.

Application filed January 5, 1899. Serial No. 701,266. Term of patent 7 years.

To all whom it may concern:

Be it known that I, WILLIAM C. HOMAN, a citizen of the United States, residing at Meriden, county of New Haven, State of Connecticut, cut, have invented and produced a certain new, useful, and original Design for a Shade-Holder, of which the following is a full, clear, and exact description.

My invention relates to a new and original design for a shade-holder, and in the illustration thereof shown in the accompanying drawings, Figure 1 represents a side elevation. Fig. 2 is a plan view.

My design comprises a plurality of ring-shaped features A and B, separated from each other by a space. Running from A to B are

a plurality of substantially straight narrow parts, each having the appearance of a narrow strip of material twisted in opposite directions. There are also narrow projections 20 D extending laterally from the part B.

What I claim, and desire to secure by Letters Patent, is—

The design for a shade-holder, substantially as herein shown and described. 25

Signed at Meriden, Connecticut, this 3d day of January, 1899.

WILLIAM C. HOMAN.
